(57) **CLAIM**

The ornamental design for a paper trimmer blade guide, as shown and described.

DESCRIPTION

FIG. 1 is a top perspective view of a paper trimmer blade guide showing our new design;

FIG. 2 is a top plan view thereof;

FIG. 3 is a bottom plan view thereof;

FIG. 4 is a front elevation thereof;

FIG. 5 is a rear elevation thereof;

FIG. 6 is a right end elevation thereof; and,

FIG. 7 is a left end elevation thereof.

The broken line showing of environment in FIG. 1 is for illustrative purposes only and forms no part of the claimed design.
